COLUMN SECTION FOR LAMP STANDARDS

Sam Bucholtz, New York, N. Y.

Application February 12, 1954, Serial No. 28,983

Term of patent 14 years

(Cl. D48—7)

To all whom it may concern:

Be it known that I, Sam Bucholtz, a citizen of the United States of America and a resident of the city of New York, in the county of Bronx and State of New York, have invented a new, original, and ornamental Design for a Column Section for Lamp Standards, of which the following is a specification, reference being had to the accompanying drawing, forming a part thereof.

Fig. 1 is a front elevational view of a column section for lamp standards, showing my new design;

Fig. 2 is a sectional plan view; and

Fig. 3 is a top view of the unit shown in Fig. 1.

The surface ornamentation shown in Fig. 1 is repeated on four alternate faces of the octagonal unit.

I claim:

The ornamental design for a column section for lamp standards, substantially as shown and described.
